Dra. J. Adams

UNITED STATES PATENT OFFICE.

OTTO VON BRONK, OF BERLIN, GERMANY, ASSIGNOR TO GESELLSCHAFT FÜR DRAHTLOSE TELEGRAPHIE M. B. H. HALLESCHIES, OF BERLIN, GERMANY, A CORPORATION OF GERMANY.

RECEIVING DETECTOR FOR WIRELESS TELEGRAPHY.

Application filed September 3, 1921. Serial No. 498,424.

(GRANTED UNDER THE PROVISIONS OF THE ACT OF MARCH 3, 1921, 41 STAT. L., 1313.)

To all whom it may concern:

Be it known that I, Otto von Bronk, citizen of the German Republic, residing at Berlin, Germany, have invented certain new and useful Improvements in Receiving Detectors for Wireless Telegraphy (for which I have filed applications in Germany, May 2, 1916, Patent No. 297,971, and in England July 8, 1920), of which the following is a specification.

In the art of wireless telegraphy it is, as is well known, very desirable for the reception of electric oscillations to admit these in tone-form, on the one hand, in order 15 to make possible a good differentiation of the reception from the atmospheric disturbances, and on the other, because the reception of musical tones is more pleasant to the ear and less fatiguing than, for instance, 20 the reception by means of ticker or slipping detector.

Various processes have become known, for receiving as tones the undamped oscillations which in themselves are inaudible. But 25 most of the known arrangements have the disadvantage that even slight fluctuations of the transmitting wave, or slight changes in the receiving devices, change the tone greatly. Thus, for instance, in the so-called 30 heterodyne-receivers (oscillation reception with auxiliary frequency) the tone wheel or the Goldschmidt frequency changer, a fluctuation of even 1% produces a change in tone of about one octave.

The present invention removes this disadvantage by utilizing a well-known principle of electrotechnics. If an alternating current dynamo which, with direct current excitation, would give the frequency N , is 35 excited with the alternating current of frequency n then there will be obtained two induced alternating potentials, namely $N+n$ and $N-n$. For the present purpose a machine will be used which has a fixed and a 40 rotating winding, inductively related to each other, and the machine can run, say, with a frequency of $N=500$ periods. With 50 revolutions it must therefore have, for instance, 20 poles. The primary winding of

the machine is now supplied with the received high frequency current (for instance $n=30000$), this winding forming, for example, a part of the antenna inductance. In the other winding there are then induced the two frequencies $n+N$ and $n-N$. Now, 55 this secondary winding can be connected to an aperiodic detector winding, with the result that the two frequencies get into interference in the detector circuit and produce a tone equal to the difference of their frequencies, i. e. $2N=1000$. 60

In the drawings Fig. 1 is a diagrammatic representation of such an arrangement by way of example. Figs. 2 and 3 illustrate refinements, and Figs. 4 and 5 are modifications. 65

In Fig. 1 reference character 1 signifies the alternating current dynamo whose fixed winding 2 is connected in the antenna 3, while the rotating winding 4 with the detector 5 and the telephone 6 with the condenser 7 connected in parallel forms the detector-circuit. 70

The secondary circuit will preferably not be made aperiodic, but, in order to attain a maximum utilization of energy and loose coupling, the two frequencies $n+N$ and $n-N$, both of which are different from the receiving wave, will be brought out through tuned circuits, by making, for instance, the induced winding 4, shown in Fig. 2, form 75 a part of the self-induction of a two-wave slightly damped circuit 8 and, which is coupled with the detector circuit 9, 5, 6, 7. The two-wave characteristic of circuit 8 is 80 attained, for instance, by connecting in parallel to a very small part of the self-induction of the circuit 8, namely, to coil 10, a correspondingly large condenser 11 (so-called flywheel-condenser). In this manner 85 a diminution of the atmospheric disturbances may be attained by the circuit represented in Fig. 3. The two wave circuit 8 is loosely coupled to tuned circuits 12 and 13, one each for the frequency $n+N$ and 90 $n-N$. By coupling these with the common detector circuit 14, 5, 6, 7, 15 then the coupling sense of each half of the detector cir-

95

cuit can be chosen at will; for instance, the coil 14 may be reversed with respect to coil 15, without any noticeable change in the reception, if the circuits 12 and 13 are sufficiently selective. But against atmospheric disturbances there will occur a weakening in the one position, because the disturbances, on account of their damped character, do not experience an exact division into two new frequencies, so that a certain compensation takes place in the common detector circuit.

The secondary circuit 8 can, as is illustrated in Fig. 4, be arranged so that it will react upon the primary circuit producing two further frequencies $n+2N$ and $n-2N$. For this purpose the secondary circuit 8 is wound either as short-circuited armature, or tuned to $N+n$ and $n-N$. By making the primary circuit three-waved by tuning it to n , $n+2N$ and $n-2N$, then there are received the tones $2N$ and $4N$. In principle, this effect is not different from the one previously described.

In all the described circuit arrangements the rotor-circuit 4, as shown in Fig. 5, can be made aperiodic. This does not change anything in principle, but makes it possible to omit the troublesome sliding contacts.

Likewise, the new frequencies which are produced in the illustrations can be secured through induction in the secondary circuit, through electric coupling (capacitive) by forming the machine 1 from a fixed and a rotating capacity, which influence each other periodically.

As the received tones are either equal to N or $2N$ or $4N$ etc., a frequency fluctuation of the sender does not change the tone at all and the tone is proportional to the number of revolutions of the receiving machine, that is, under normal conditions, the percentage variation will be small.

The machine can also be used for receiving tone transmitters so that the transmitted note is maintained. This is a great advantage of the apparatus, which is not present in any other of the usual methods of tone-reception of undamped oscillations. In this case the machine is allowed to run with a frequency which does not deviate too much from the number of sparks, but on the other hand deviates sufficiently that the beats between alternator frequency and spark frequency can no longer be discerned by the ear, i. e. amount to at least 20 per second. If the transmitter has the tone 1000 the machine will be run with frequencies of about 800 to 980 and 1020 to 1200. This has the advantage that the number of revolutions can be fixed so that a foreign, disturbing tone-transmitter which has a different tone is greatly subdued, apparently, because in consequence of the rotation the secondary circuit is being periodically uncoupled from

the antenna, so that a large part of the disturbances cannot enter into the secondary circuit.

Having described my invention, what I claim is:

1. The method of receiving electrical oscillations and minimizing interference due to aperiodic disturbances in which the received signal currents are combined with a low frequency to affect a common detector circuit comprising, combining the signal currents with the low frequency to produce two new high frequency currents, impressing said new high frequency currents, on the common detector circuit and selecting a sense of coupling with the detector circuit which minimizes the effect of aperiodic disturbances.

2. The method of receiving electrical oscillations in which the incoming high frequency oscillations are used for the excitation of an alternating current dynamo possessing a natural frequency of its own comprising heterodyning the frequencies obtained by the combining of the signal frequency oscillations and the natural frequency of the dynamo, to produce an audible beat.

3. The method of receiving electrical oscillations in which the incoming high frequency oscillations are used for the excitation of an alternating current generator possessing a natural frequency of its own which modulates the incoming frequency so as to produce new frequencies, comprising causing the new frequencies to interfere with each other so that a note of double the natural frequency of the generator is produced.

4. In combination, an alternating current generator, signal receiving means connected to the field of said generator, a circuit connected to the armature of said generator, said circuit being arranged to resonate simultaneously the frequencies equal to the sum and difference of the signal frequency and natural generator frequency.

5. In combination, an alternating current generator, signal receiving means connected to the field of said generator, a circuit connected to the armature of said generator, said circuit being arranged to resonate simultaneously the frequencies equal to the sum and difference of the signal frequency and natural generator frequency and means for combining said resonance frequencies to produce a beat equal to a multiple of the natural generator frequency.

6. In combination, an alternating current generator, signal receiving means connected to the field of said generator, a circuit connected to the armature of said generator, said circuit being arranged to resonate simultaneously the frequencies equal to the sum and difference of the signal frequency

and natural generator frequency, intermediate circuits coupled to said armature circuit, one of said intermediate circuits being tuned to one of said resonance frequencies, the other being tuned to the other resonance frequency, a detector circuit coupled to said intermediate circuits, the sense of coupling

being arranged so that disturbing oscillations received by the said receiving means oppose each other in their effect on said detector circuit. 10

In testimony whereof I affix my signature.

OTTO von BRONK.
